FEED REGULATOR FOR SEWING MACHINES

Alfred R. Wood, Bridgeport, Conn., assignor to
The Singer Manufacturing Company, Elizabeth,
N. J., a corporation of New Jersey

Application December 13, 1941, Serial No. 422,790

12 Claims. (Cl. 112—73)

This invention relates to sewing machines and more particularly to an improvement in feed-regulators for buttonhole sewing machines of the type disclosed in the U. S. patent to E. B. Allen, No. 784,291, issued March 7, 1905.

In the use of buttonhole sewing machines it is frequently necessary when changing from one character of work to another that the number of stitches required in the entire buttonhole be varied. It is, of course, desirable that the buttonhole machine be equipped with a suitable feed-regulator which will provide means conveniently accessible for manipulation by the operator by which the number of stitches produced in the buttonhole may be varied. It is toward the solution of this problem that applicant has addressed himself.

In prior machines of the type illustrated in the above mentioned Allen patent, means were provided by which the number of stitches in the buttonhole could be controlled. However, in effecting an adjustment of said means it was necessary to displace the machine out of its normal operating position in order to expose the adjusting means which was located on the under-side of the machine-bed. This required displacement of the machine from its normal operating position has been troublesome, particularly to female operators because of the weight of the machine. Moreover, since no micrometer adjustment was provided on the prior machines a trial-and-error method had to be followed in order to obtain the correct number of stitches in the buttonhole. During the procedure of obtaining the proper number of stitches, the sewing machine had to be repeatedly tilted backwardly between adjustments, thus requiring the expenditure of considerable effort by the operator in endeavoring to obtain the desired number of stitches in the buttonhole.

Therefore, it is the primary object of the present invention to provide an improved feed-regulator for buttonhole machines which will permit the adjustment of the number of stitches in the buttonhole without having to displace the buttonhole machine from its normal operating position.

It is a further object of the invention to provide an improved feed-regulator for buttonhole machines with which major or minor adjustments can be accomplished with equal facility.

Another object of the present invention is the provision of an improved feed-regulator device which is self-contained and adapted for con-

venient application upon machines already in the trade.

A further object of the present invention is the provision of a feed-regulator designed so that adjustment of the number of stitches comprising the buttonhole may be made over a wide range.

A still further object of the present invention is the provision of a feed-regulator for button-hole machines which is capable of being operated to change the number of stitches in a button-hole during the operation of the machine.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

The invention will best be understood by referring to the accompanying drawings, in which:

Fig. 1 is a right side elevational view of a "Singer Class 71" buttonhole sewing machine equipped with a preferred form of the invention, showing the machine in full lines and the supporting base upon which the machine rests in dot-dash lines.

Fig. 2 is a bottom plan view of the machine shown in Fig. 1, with the wrench used to adjust the feed-regulator in dotted lines.

Fig. 3 is a vertical sectional view taken through the standard of the machine, showing the driving connections between the main-shaft and the feed-shaft actuating clutch.

Fig. 4 is an enlarged vertical sectional view taken transversely of the slotted arcuate clutch-actuating arm and through the slide-block mounted thereon, showing the link connection with the slide-block; the parts illustrated being shown in an inverted position.

Fig. 5 is an enlarged horizontal sectional view taken through the right angle bracket, which is freely fulcrumed upon lower end of the feed-shaft, showing the bevel-gear connection between the threaded adjusting rod and the wrench-receiving spindle.

Fig. 6 is an enlarged vertical sectional view taken substantially along the line 6—6, Fig. 2.

Fig. 7 is a vertical sectional view taken through the bed, illustrating a modification of the feed-regulator.

Fig. 8 is a vertical sectional view taken substantially along the line 8—8, Fig. 7.

Fig. 9 is a left side elevational view of the

parts illustrated in Fig. 7 with the bed removed. Referring more in detail to the drawings, the invention is shown as embodied in a sewing machine comprising a frame including a rectangular bed 1 from one end of which rises a standard 2 of an overhanging bracket-arm 3 terminating in a head 4. Journaled in the bracket-arm 3 is a belt-driven main-shaft 5 connected in the head 4 to the usual endwise reciprocating and laterally vibratory needle-bar 6 carrying a needle 7. Complementary to the needle 7 in the formation of lock-stitches is a conventional oscillating shuttle 8 driven by the bed-shaft 9 operatively connected to the main-shaft 5 in a manner represented in U. S. Patent No. 784,291, issued to E. B. Allen, on March 7, 1905.

As is customary in machines of the type selected to illustrate the present invention, the work to be sewn is retained in a work-clamp represented by the reference numeral 10. By means of the work-clamp the work is slowly moved step-by-step fashion under the endwise reciprocating and laterally vibratory needle 7, first away from the standard 2 and then towards the standard to cause the first and second rows of side zigzag stitches to be laid side by side in the work. At the ends of the rows of side stitches the usual groups of barring stitches may be formed provided the machine is fitted with a barring device. The work-clamp 10 derives its step-by-step movements from a feed-cam 11 secured upon the lower end of a feed-shaft 12; the connections between the work-clamp and feed-cam being constructed substantially in accordance with the disclosure in the U. S. Patent No. 785,061, issued to E. B. Allen, on March 14, 1905.

The feed-shaft 12 is operatively connected to the main-shaft 5 through mechanism designed to impart intermittent rotary movement to the feed-shaft. It is to an improvement in a portion of this mechanism that the present invention is directed.

As shown in Figs. 2 and 3, the main-shaft 5 has fixed thereon an eccentric 13 embraced by the upper end of a pitman 14 connected at its lower end to the horizontal arm 15 of a tubular rock-shaft 16 journaled upon a pivot-rod 17 fixed in the lugs 18, 19 depending from the bed 1. Depending from the tubular rock-shaft 16 and preferably formed integrally therewith is an arm 19 provided at its lower end with a spherical portion 20 embraced by one end of a link 21 of which the other end embraces a spherical portion 22 provided on a pivot-block 23 adjustably mounted on a slotted arcuate clutch-actuating arm 24. The clutch-actuating arm (Fig. 2) at one end is secured by three screws 25 and a locating pin 26 to the bottom face of an internal spider or clutch-plate 27 which is formed with three peripheral notches 28 having slightly eccentric bottom walls 29. The internal clutch-plate 27 is received within the recessed bottom face of the feed-cam 11 having a flange 30 which, together with the walls of the notches 28 form pockets for the reception of clutch-members 31, which in the preferred form comprise cylinders or balls. Springs 32 within the pockets normally bias the clutch-members 31 in a direction to wedge them between the concentric inner face of the flange 30 and the eccentric bottom walls 29 of the respective notches 28, thereby establishing driving relation between the internal clutch-plate 27 and the feed-cam 11. By means of the clutch just described the feed-cam 11 and the feed-shaft 12 are intermittently rotated in timed relation

with the stitch-forming mechanism to properly shift the work-clamp and produce the desired buttonhole or tack determined by the cam grooves cut in the feed-cam 11.

5 The internal clutch-plate 27 and the clutch-cylinders 31 are retained in position within the flange 30 provided on the feed-cam 11 by means of a spring-plate 33 which is secured upon the reduced lower end-portion 34 of the feed-shaft 12 by a nut 35, see Fig. 6.

10 It will be understood from the accompanying drawings taken in connection with the above description that the amount of turn imparted to the feed-shaft for each rotation of the main-shaft 5 depends upon the distance the slide-block 23 is removed from the longitudinal axis of the feed-shaft 12, and that by varying this distance the amount of turn imparted to the feed-shaft and consequently the spacing between successive stitches in the buttonhole or tack may be controlled.

15 The preferred means employed for shifting the slide-block 23 lengthwise of the clutch-actuating arm 24 comprises a screw-threaded rod 36 having threaded thereon intermediate its ends spaced ears 37 depending from the slide-block 23. As shown in Fig. 4, the slide block 23 is preferably attached to the clutch-actuating arm 24 by means of a slide 38 located in the T-shaped slot 39 of the clutch-actuating arm which slide 38 is pivotally secured to the slide-block 23 by the stud 40. As will be observed in Fig. 5 the screw-threaded rod 36 is journaled at its inner end in a supporting bracket 41 freely fulcrumed upon the reduced lower end-portion 34 of the feed-shaft 12 and retained thereon by means of a cap-screw 42. In order to rotate the screw-threaded bar 36, thereby to shift the slide-block 23 lengthwise of the clutch-actuating arm 24 toward or 20 away from the axis of the feed-shaft 12, the rod 36 is preferably provided on its inner end with a bevel gear 43 in mesh with a second bevel gear 44 fixed on one end of a short spindle 45 disposed normal to the screw-threaded rod 36 and journaled in the supporting bracket 41. The screw-threaded rod 36 is prevented from moving endwise relative to its supporting bracket 41 by the gear 43 and a collar 43' which is secured on the rod 36 by a set-screw 43'' (Fig. 5). The 25 outer end of the spindle 45 is formed into a tapered hexagonal head 46 disposed to conveniently receive the end of a wrench 47 (shown in dotted lines in Fig. 2) adapted to be inserted through a suitable clearance aperture 48 provided in the side wall of the usual machine-supporting frame 49, shown in dot-dash lines in Fig. 1. With the aid of the wrench 47, the rod 36 can be easily turned, and hence the spacing between the stitches increased or decreased, without having to tilt or displace the machine from its normal operating position. The taper on the hexagonal head 46 is desirable for the reason that it facilitates the placing of the wrench upon the head whether the machine is at rest or in operation.

30 In order to prevent accidental turning of the screw-threaded rod 36, means is provided for locking the rod in set position. This means is best shown in Fig. 2 and comprises a resilient detent 50 secured upon the supporting bracket 41, which detent cooperates with a plurality of serrations 51 formed in the peripheral surface of the hub of the bevel-gear 43.

35 Figs. 7, 8 and 9 disclose a modified form of feed-regulator. In this form the lower end of the pitman 14 is adjustably connected to the

horizontal arm on the tubular rock-shaft 16, whereby the effective length of the horizontal arm is lengthened or shortened and hence the amplitude of the oscillations of the clutch-actuating arm is proportionally lengthened or shortened. As shown in Fig. 7, the tubular rock-shaft 16 is formed with an arm 52 slotted as at 53 to receive a slide-block 54 to which is connected by a stud 55 the lower end of the pitman 14. Attached to the depending extension 56 of the slide-block 54 (Fig. 8) by means of a tongue-and-groove connection and screw 57 is a block 58 threaded to receive an adjusting rod 59 secured against endwise movement in projections 60 and 61 provided on the horizontal arm 52, see Fig. 7. Formed on the outer end of the adjusting rod 59 is a hexagonal head 62 accessible to a wrench through a clearance opening 63 formed in the depending side-wall 64 of the bed 1.

It will be understood that by turning the adjusting rod 59, with the aid of the wrench, the slide-block 54 will be shifted lengthwise of the slotted horizontal arm 52, thereby changing the effective length of the arm 52 and consequently imparting more or less oscillation to the clutch-actuating arm 24. Obviously the range of adjustment of the modification shown in Figs. 7, 8 and 9, as compared to that shown in Fig. 2, is considerably less, but for many classes of work is quite sufficient. Also, it will be appreciated that both forms of design may be incorporated in one machine, in which case one device can be adjusted to augment the action of the other device and thereby increase or decrease the magnitude of variation in the number of stitches comprising the buttonhole.

From the above description, taken in connection with the accompanying drawings, it will be understood that there has been devised an improved feed-regulator particularly for use in buttonhole sewing machines, which feed-regulator will permit the convenient adjustment of the number of stitches in the buttonhole while the machine is in its normal operating position and regardless of whether the adjustment desired is of major or minor character. While the rod-engaging end of the wrench disclosed is of conventional design, it will be obvious that the design may be made special, in which case the wrench could serve as a key and only persons authorized to change the number of stitches in the buttonhole could do so.

While only two modifications of the improved feed-regulator have been disclosed, it is obvious that other forms may be made and it is my desire to include as part of this invention all forms of the device which fall within the purview of the appended claims. Further, I have chosen, for illustration purposes only, a conventional "Horton" clutch as the intermittent actuated device of the work-clamp shifting mechanism, but it is to be understood that other forms of intermittent actuated devices may be used, such for instance as the device illustrated in the U. S. patent to E. B. Allen, No. 784,291, dated March 7, 1905.

Having thus set forth the nature of the invention what I claim herein is:

1. A group-stitch sewing machine having, in combination, a frame, a work-clamp, and means for imparting work-advancing movements to said work-clamp including, an intermittent actuated device, an arm connected with said intermittent actuated device and having an arcuate longitudinal slot formed therein, a slide-block adjustably

received in said slot, actuating mechanism connected to said slide-block for imparting oscillations to said arm, and a pivotally mounted screw-threaded adjusting rod disposed lengthwise of said slot and threaded into said slide-block, said adjusting rod having means at one end adapted to receive a wrench by which the adjusting rod can be conveniently turned to move the slide-block lengthwise of said arm.

2. A group-stitch sewing machine having, in combination, a frame, a work-clamp, and means for imparting work-advancing movements to said work-clamp including, an intermittent actuated device mounted to operate about a fixed axis, an arm connected to said intermittent actuated device and formed with an arcuate elongated slot, a slide-block adjustably mounted in said slot, actuating mechanism connected to said slide-block for imparting oscillations to said arm, a screw-threaded adjusting rod disposed lengthwise of said arm and threaded into said slide-block, said adjusting rod being supported to turn freely about an axis in alignment with the axis of said intermittent actuated device, and means provided at one end of said adjusting rod adapted to receive a wrench by which the adjusting rod can be conveniently turned to shift the slide-block lengthwise of said slot.

3. In a group-stitch sewing machine having a frame, a feed-shaft, an intermittent actuated device operatively connected to said feed-shaft, an arm connected to said feed-shaft and formed with an arcuate elongated slot, a slide-block adjustably mounted in said slot, actuating mechanism connected to said slide-block for imparting oscillations to said arm, a supporting bracket freely journaled upon said feed-shaft adjacent said arm, a screw-threaded adjusting rod secured against endwise movement in said bracket and disposed lengthwise of said elongated slot, said adjusting rod being threaded into said slide-block, and means provided at one end of said adjusting rod adapted to receive a wrench by which the adjusting rod can be conveniently turned to shift the slide-block lengthwise of said slot.

4. In a group-stitch sewing machine having a frame, a work-clamp, and means for imparting work-advancing movements to said work-clamp including, an intermittent actuated device, an actuating arm connected with said device, a slide-block, means securing said slide-block on said actuating arm and permitting adjustment of said slide-block lengthwise of said arm, actuating mechanism connected to said slide-block for imparting movement to said actuating arm, a screw-threaded adjusting rod disposed lengthwise of said arm and threaded into said slide-block, a spindle having an axis disposed at an angle to the axis of said adjusting rod, means operatively connecting said spindle with said adjusting rod, and means provided on said spindle by which it can be conveniently turned to rotate said adjusting rod and shift the slide-block lengthwise of said arm.

5. In a group-stitch sewing machine having a frame, a work-clamp, and means for imparting work-advancing movements to said work-clamp including, an intermittent actuated device, an actuating arm connected with said device, a slide-block, means securing said slide-block on said actuating arm and permitting adjustment of said slide-block lengthwise of said arm, actuating mechanism connected to said slide-block for im-

parting movement to said actuating arm, a screw-threaded adjusting rod disposed lengthwise of said arm and threaded into said slide-block, a spindle having an axis disposed at an angle to the axis of said adjusting rod, means operatively connecting said spindle with said adjusting rod, means preventing accidental turning of said adjusting rod, and means provided on said spindle by which it can be conveniently turned to rotate said adjusting rod and shift the slide-block lengthwise of said arm.

6. In a group-stitch sewing machine having a frame, a work-clamp, and means for imparting work-advancing movements to said work-clamp including, an intermittent actuated device, an actuating arm connected with said device, a slide-block, means securing said slide-block on said actuating arm and permitting adjustment of said slide-block lengthwise of said arm, mechanism connected to said slide-block for imparting movement to said actuating arm, a screw-threaded adjusting rod disposed lengthwise of said arm and threaded into said slide-block, a gear mounted on said adjusting rod, a spindle having an axis disposed at an angle to the axis of said adjusting rod, a gear mounted on said spindle and in mesh with the gear on said adjusting rod, and means provided on said spindle by which it can be conveniently turned to rotate said adjusting rod and shift the slide-block lengthwise of said arm.

7. In a group-stitch sewing machine having a frame, a work-clamp, and means for imparting work-advancing movements to said work-clamp including, an intermittent actuated device, an actuating arm connected with said device and formed with an arcuate elongated slot, a slide-block adjustably mounted in said slot, actuating mechanism connected to said slide-block for imparting oscillations to said actuating arm, a pivotally mounted supporting bracket positioned adjacent said actuating arm, a screw-threaded adjusting rod rotatably mounted in said bracket and disposed lengthwise of said elongated slot, said adjusting rod being threaded into said slide-block, a gear fixed on said adjusting rod, a spindle journaled in said supporting bracket and arranged at an angle to said adjusting rod, a gear fixed on said spindle and in mesh with the gear on said adjusting rod, and means provided on one end of said spindle to receive a wrench by which the adjusting rod can be turned to shift the slide-block lengthwise of said slot.

8. In a group-stitch sewing machine having a frame, a work-clamp, and means for imparting work-advancing movements to said work-clamp including, an intermittent actuated device mounted to operate about a fixed axis, an actuating arm connected to said intermittent actuated device and mounted for oscillatory movements about said fixed axis of said intermittent actuated device, said actuating arm formed with an arcuate elongated slot, a slide-block adjustably mounted in said slot, operating mechanism connected to said slide-block for imparting oscillations to said actuating arm, a supporting bracket positioned adjacent said actuating arm and fulcrumed for free turning movement about the fixed axis of said intermittent actuated device, a screw-threaded adjusting rod rotatably mounted in said bracket and disposed lengthwise of said elongated slot, said adjusting rod being threaded into said slide-block, a gear fixed on said adjusting rod, a spindle journaled in said supporting bracket and arranged at an angle to said adjusting rod, a gear fixed on said spindle

and in mesh with the gear on said adjusting rod, and means provided on one end of said spindle to receive a wrench by which the adjusting rod can be turned to shift the slide-block lengthwise of said slot.

9. A group-stitch sewing machine having, in combination, a frame, stitch-forming mechanism including a needle, a work-clamp, and means for imparting relative movements between said work-clamp and needle including, an intermittent actuated device, an arm connected with said intermittent actuated device and having an arcuate longitudinal slot formed therein, a slide-block adjustably received in said slot, actuating mechanism connected to said slide-block for imparting oscillations to said arm, and means for shifting said slide-block in said arcuate slot, said last-named means including a bracket located beneath said intermittent actuated device and supported for swinging movement, a screw-threaded adjusting rod journaled for rotation in said bracket and threaded into said slide-block, means for securing said screw-threaded adjusting rod against endwise movement relative to said bracket, and means provided at one end of said screw-threaded adjusting rod adapted to receive a wrench by which the adjusting rod can be conveniently rotated to move the slide-block lengthwise of said arm.

10. In a buttonhole sewing machine having a frame including a bracket-arm and a bed-structure provided with a clearance aperture, a feed-shaft journaled in said frame and having its lower end extending within said bed-structure, an intermittent actuated device operatively connected to the lower end of said feed-shaft, mechanism for operating said intermittent actuated device including an arm formed with an arcuate slot, a slide-block adjustably mounted in said slot, an operating member connected to said slide-block, a bracket located beneath said intermittent actuated device and supported for swinging movement, a screw-threaded adjusting rod journaled for rotation in said bracket and threaded into said slide-block, means for securing said screw-threaded adjusting rod against endwise movement relative to said bracket, means provided at one end of said adjusting rod adapted to receive a wrench extending through the clearance aperture in said bed-structure by which the adjusting rod can be rotated to shift the slide-block lengthwise of said slot, and means for preventing accidental rotation of the adjusting rod during the operation of the machine.

11. A group-stitch sewing machine having, in combination, a frame, stitch-forming mechanism including a needle, a work-clamp, and means for imparting relative movements between said work-clamp and needle including, an intermittent actuated device, an arm connected with said intermittent actuated device and having an arcuate longitudinal slot formed therein, a slide-block adjustably received in said slot, actuating mechanism connected to said slide-block for imparting oscillations to said arm, and means for shifting said slide-block in said arcuate slot, said last-named means including a pivotal bracket located beneath said intermittent actuated device and supported for swinging movement about an axis, a screw-threaded adjusting rod journaled for rotation in said bracket and threaded into said slide-block, means for securing said screw-threaded adjusting rod against endwise movement relative to said bracket, and means provided at

that end of said screw-thread adjusting rod adjacent the pivotal axis of said bracket adapted to receive a wrench by which the adjusting rod can be conveniently rotated to move the slide-block lengthwise of said arm.

12. A feed-regulator adapted for use in a group-stitch sewing machine having a feed-shaft, comprising, an intermittent actuated device for imparting operative movements to said feed-shaft, an arm secured to said intermittent actuated de-

vice and having an arcuate slot formed therein, a slide disposed in said slot, a pivot-block fulcrumed on said slide and adapted to be connected to mechanism for oscillating said arm about the axis of said feed-shaft, a bracket, means pivotally supporting said bracket, and a screw-threaded adjusting screw journaled in said bracket and threaded into said pivot-block.

ALFRED R. WOOD.
